UNITED STATES PATENT OFFICE

ROBERT ROTHMAN, OF BROOKLYN, NEW YORK.

KNIT FABRIC.

Application filed December 26, 1924. Serial No. 757,994.

To all whom it may concern:

Be it known that I, ROBERT ROTHMAN, a native of Russia (who has applied for citizenship of the United States), and a resident of Brooklyn, county of Kings, State of New York, have invented certain new and useful Improvements in Knit Fabrics, of which the following is a specification.

10 The object of the present invention is to produce a knit fabric in which ribs are produced extending longitudinally, between which plain or other form of knit fabric is interposed, and which ribs will have a 15 thickness substantially triple that of the knit fabric beyond the rib, and which ribs will be comparatively narrow and comprise a continuous wale.

In the accompanying drawing showing 20 one embodiment of my invention, Figure 1 shows a portion of the fabric somewhat enlarged.

Fig. 2, is an edge view of the fabric as shown in Fig. 1.

25 Fig. 3 is a somewhat diagrammatic view of the method of knitting with the loops obviously shown in the open position.

Fig. 4 is a similar view with the loops corresponding more nearly to the structure 30 of Fig. 1.

This invention consists essentially of a knit fabric having at intervals preferably remote, a continuous wale formed of multiple threads, such as three or more threads, 35 each of which is taken from the single course thread in the fabric on each side of such wale, extending between these enlarged wales. As shown herein the band of plain or ordinary knit extends between the 40 multiple thread wales, but any desired form of a knit may be interposed between these multiple thread wales, or might be brought adjacent.

In Fig. 3 of the drawing I show a series 45 of multiple thread wales indicated generally by 4, that are formed out of three courses of the single thread, and indicated by 1, 2 and 3. On each side of the multiple wale loop 4 are plain loops 5 and 6, each 50 composed of a single thread. It will be seen that the threads 1, 2 and 3 pass downwardly through the loops 10, 11 and 12 respectively, as at 7, 8 and 9, and then pass 55 through the multiple thread loop 40 formed similarly of three threads which three threads then pass upwardly as at 13 and

form loop 4, where they engage two multiple thread loops 14 and 15; thence these three threads pass downwardly at 16, and again go through the multiple thread loop 40, pass upwardly through the side loops 60 17, 18 and 19 respectively and continue on the left as the same three course threads 1, 2 and 3. It will be seen that the multiple thread loop 40 is formed in precisely the same manner by the course threads 21, 22 and 23, that pass through the similar lower loop 20 and coming upwardly engage the loop portions formed by the multiple threads 13 and 16 at their lower portions. 65 From this arrangement it follows that the multiple loops in the wales will each be three times the length of one loop on each side and this will extend for the distance of three side loops. In the same manner 70 four threads might be used, or more to form multiple thread loops that might extend for the distance of four course loops. 75

The arrangement in Fig. 3 is somewhat theoretical; as in the production of this fabric on the usual circular knitting machine will produce the effect as indicated in Fig. 1. The method followed is simply to take predetermined needles spaced the 80 same number of needles apart, such as each seventh needle, and then arrange the sinkers or other mechanism, whereby these needles in two successive courses of the wale will not knit off, but the thread or float 85 will remain there until the third course is made on each of these needles, that will then knit off as usual. This will produce a multiple thread loop each third course and the same multiple thread loop will be 90 knit through the one previously formed. 95 This operation by holding the two thread floats naturally places a considerable tension thereon, as well as the two knit off, and naturally the adjacent loop wales are drawn upon to supply the extra thread 100 needed. This will have the general effect of making the adjacent wales on each side of the multiple wales, narrow and contracted, and the intermediate wale loops will 105 be wider than the normal loop in the plain knit, or one without the multiple wales, as indicated in Fig. 1. Here the multiple wale loops have about the same width as the other wale loops beyond the wale loops containing the multiple thread wales. It has 110 been found that this bringing together the three threads in the multiple loops will

make the thickness or rib at these portions three times the normal thickness of the fabric as knit between these ribs. This is further assisted by the narrow and tight knit 5 wales adjoining the multiple wale on each side, which braces the multiple wale loops and maintains this effect.

By this operation, various artistic effects can be produced, by different designs of the 10 fabric between the multiple wales, such as the ordinary rib formed by reversing the loops alternately, also three different colored threads can be used in the successive courses, and produce loops in the plain courses between the multiple thread wales in alternate 15 courses, while each multiple thread loop would have three threads brought together and a contrasting effect would result. Also the three threads in one course might 20 by any one color, and the next three threads in a different color, that would show the ribs in different colors in different portions.

Another very beneficial result of this fabric is that it possesses exceptional strength 25 lengthwise of the ribs, and cannot stretch or sag in this direction. Also the lateral sag or stretch is reduced, because the loops in the wales are already considerably stretched to produce the multiple thread ribs, and the 30 knit is comparatively tight.

The fabric as shown in Fig. 4 is substantially as it is produced in the knitting machine. It is customary to treat such fabrics by a cleaning operation which usually 35 employs steam and sometimes soap or detergents. These operations will have the effect of causing the ribs adjoining the multiple thread wale that are tightly drawn to somewhat relax and this operation will 40 cause wider loops between the rib portion to receive more thread and that will somewhat close up and impart more nearly uniform appearance to the fabric.

What I claim is:

45 1. In a knit fabric, a wale of multiple threads in each successive loop, such wale being interposed between wales, in which each group of three adjacent course threads on each side are brought together to form 50 a series of successive multiple thread loops in the form of a knit wale.

55 2. In a knit fabric, a wale in which the successive knit loops are each composed of three threads from three adjacent courses on each side of the wale.

60 3. In a knit fabric, a wale of multiple threads in each successive loop, such wale being interposed between plain knit wales, in which each group of three adjacent course 65 threads on each side are brought together to form a series of successive multiple thread loops in form of a knit wale, whereby is

produced a rib of triple thickness compared with the thickness of the plain knit wales adjacent this wale.

65

4. In a knit fabric, a needle wale of multiple threads in each successive loop, such wale being interposed between needle wales in which each group of three adjacent course threads on each side are brought to form 70 a series of successive multiple thread loops in form of a knit wale, each said multiple thread wale having the adjacent needle wales on each side considerably narrower than the multiple wale, and the needle wales 75 beyond said narrow wales being of substantially the same width as the said multiple thread wale loops.

70

5. In a knit fabric, a needle wale of multiple threads in each successive loop, such 80 wale being interposed between plain knit needle wales, in which each group of three adjacent course threads on each side are brought together to form a series of successive multiple thread loops in the form of 85 a knit wale, each said multiple thread wale loop having the adjacent needle wale loops on each side considerably narrower than the multiple wale loop, and the needle wale loops beyond said narrow wales being of 90 substantially the same width as the said multiple thread wale loops.

85

6. The method of producing a multiple thread wale in a knit fabric, which consists in holding a thread on a predetermined 95 needle for two successive courses, thereupon knitting these two course threads with also the next and third successive course thread off the needle, to knit in the three threads together, in one loop, thereupon repeating the operation for the fourth, fifth and sixth 100 courses on the same needle by looping through the said triple thread loop just formed, and knitting off again on the sixth course, and repeating the operation.

100

7. The method of producing a multiple thread wale in a knit fabric, which consists in holding the thread on a predetermined needle for two successive courses, thereupon knitting these two course threads with also the next and third successive course thread off the needle, to knit in the three threads together, thereupon repeating the operation for the fourth, fifth and sixth 110 courses on the same needle by looping through the said triple thread loop just formed, and knitting off on the sixth course, the first thread that is floated across said predetermined needle being given a certain amount of slack to provide extra thread for 115 the multiple loop.

110

Signed at New York, N. Y., on December 23, 1924.
